INVENTOR:

RUDOLF HEIMERS,

by Carl A. Hellmann

ATTORNEY.

UNITED STATES PATENT OFFICE

2,110,084

BALL GAME

Rudolf Heimers, Mexico, D. F., Mexico

Original application August 7, 1934, Serial No. 738,876. Divided and this application June 1, 1937, Serial No. 145,902. In Mexico August 11, 1933

5 Claims. (Cl. 273—97)

The invention relates to ball games, and more especially to games in which the ball is attached to an elastic string and after being thrown returns automatically towards the throwing or striking surface. The new feature of the invention consists in passing the elastic string through friction-reducing means provided in the striking or throwing surface, and in using a longer elastic, so as to enable the player to throw the ball at a much greater distance with the same ease than with a shorter elastic.

The invention has for its object to provide means whereby the length of the elastic may be adapted to the skill of the player, so that the ball may either remain separated for a greater or lesser distance from the striking or throwing surface after it has returned through the contraction of the elastic, or may be forced to return completely into contact with said surface, which- 20 ever may be the length of the elastic or the force with which the ball was thrown, but always permitting the ball to be thrown at a much greater distance due to the greater length of the elastic string.

25 The features of the invention comprising friction-reducing means, located in the striking or throwing surface for enabling the elastic string to pass without excessive friction, and means for attaching a long elastic to the body of the player or housing it in the throwing implement itself, it will be readily understood that these features may be applied to a variety of differently shaped throwing devices, such as bats, rackets and others, providing a great diversity of games based 30 on the same principle.

This application is a division of application Serial No. 738,876, filed August 7, 1934.

In the accompanying drawing, in which several preferred embodiments of the invention are 40 shown:

Figure 1 is a front view of an oval throwing board with the elastic rolled up on a wheel with twisted axle.

Figure 2 is a transversal vertical cross-section of the device shown in Figure 1.

Figure 3 is a detailed view of the wheel with twisted axle.

Figure 4 shows a tennis racket provided with a friction-reducing attachment and with the elastic housed in the handle.

Figure 5 is a side view of the racket, with the handle shown in cross-section.

Figure 6 is a detailed view of the detachable friction-reducing attachment.

Figure 7 shows the bracket with wheels attached to the top of the racket.

Figure 8 is a sectional view of the hollow cover with wheels entering the lower extremity of the racket handle.

Figure 9 shows an outer attachment for the handle with wheels around which the elastic is wound.

Figure 10 is a back view of another tennis racket with a detachable frame holding the 10 wheels and the friction-reducing device.

Figure 11 is a detailed view of this frame.

The following devices to be described all make use of an improved friction-reducing device comprising two pairs of rollers 7, with one pair placed 15 at right angle to the other, said rollers turning on conical points entering the sides of a separate casing. As the elastic 5 passes through the central opening of said pairs of rollers, the friction is greatly reduced by the revolving rollers.

In the device shown in Figures 1 and 2, an oval board 8 is attached to a hollow handle 9. The friction-reducing rollers 7 are located within the center of the board 8 and the elastic 5, attached to the ball 4, passes back of the board 8 into 25 the handle 9 and is wound around a spool 10 provided in the lower part of said handle. The spool 10 has two elastic strings 11 passing through it (Figure 3) which are already twisted to keep the elastic stretched and which twist themselves 30 more tightly as the elastic is unwound from the spool, rotating therefore in an opposite direction the spool on which the elastic winds itself as the ball returns after having been thrown by the board 8.

35 Figures 4, 5 and 10 show the friction-reducing rollers 7 attached to a tennis racket 12. The rollers 7 are housed in a casing 13 (Figure 6) provided on opposite sides with U-shaped channels 14 into which enter two of the central strings 40 of the racket. The elastic 5 passes between said rollers 7 to the back of the racket, and from there is led upward and downward in several turns around two sets of wheels or rollers 15, the upper set of which is fixed to a bracket 16 attached to the upper part of the racket, and the lower set is placed on a transversal axle in a hollow cover 17 which closes the open lower extremity of the hollow racket handle. A wire 18 having an upper eye is also secured with its lower 45 extremity inside of said cover 17 and serves to pull the end of the elastic through the handle when a new string is being inserted. The ball 4 may be held against the handle of the racket by a spring 19 when the racket is to be used for 50 55

playing with a free ball, but may be instantly released when it is desired to use the ball attached to the elastic.

Figure 9 shows a spring clip bracket 20 carrying the lower set of rollers 15, which may be slipped on the handle of a racket instead of using the hollow handle shown in Figure 5. The two attachments 7 and 20 may therefore be used on any tennis racket for practice purposes, and the only other attachment 16 for the upper set of rollers 15 may be held by a thumbnut or other detachable means, the relatively great length of the elastic stretched between the rollers 15 being sufficient for permitting the ball to be thrown a great distance and at different angles.

In Figure 10, the upper rollers 15 are placed on the upper part of a wire frame 21 to which are also slidably attached the casing 13 for the friction-reducing rollers 7 and a bracket 22 similar to bracket 20 and supporting the lower set of rollers 15. This frame is held in place by the bracket 22 and the casing 13, and may also be attached to any tennis racket and taken off at will.

What I claim is:—

1. A ball game, comprising an elastic attached at one end to a ball, a racket, a friction reducing guide comprising pairs of crossed rollers detachably secured to said racket, and means attached to the racket and comprising a plurality of rollers for winding upon them a plurality of turns of the elastic.

2. A ball game, comprising a ball, an elastic attached to said ball, a racket, friction reducing means comprising crossed pairs of rollers de-

tachably secured to the strings of said racket, said elastic passing through said friction-reducing means, and means attached to said racket and comprising a plurality of rollers for winding upon them a plurality of turns of the elastic.

3. A ball game, comprising a racket having a hollow handle, friction-reducing means secured to the strings of the racket, an elastic passing through said friction-reducing means, a ball attached to said elastic, a set of rollers provided on the upper part of said racket on the side opposite to the ball, a second set of rollers mounted within the hollow handle, the elastic being led around said upper and lower rollers, means for pulling the elastic through said hollow handle, and means for detaining the ball out of contact with the striking surface of the racket.

4. A ball game, comprising a racket, a frame holding friction-reducing means comprising crossed pairs of rollers, an upper and a lower set of rollers attached to said frame, a bracket holding said frame to the handle of said racket, means for holding the friction-reducing means between the strings of the racket, a ball, and an elastic attached to said ball, said elastic passing through said friction-reducing means and being wound alternatively around said upper and lower rollers.

5. A ball game, comprising an elastic attached at one end to a ball, a racket, a friction reducing guide detachably secured to said racket, and means attached to the racket and comprising a plurality of rollers for winding upon them a plurality of turns of the elastic.

RUDOLF HEIMERS. 35
